US0D1011849S

(12) **United States Design Patent** (10) **Patent No.:** **US D1,011,849 S**
(45) **Date of Patent:** **** Jan. 23, 2024**

(54) **CHEMICAL ROLLER HEAD CORE**

(71) Applicant: **University of Tennessee Research Foundation**, Knoxville, TN (US)

(72) Inventors: **Parker Michael Alperin**, Germantown, TN (US); **Charles William Beasley**, Signal Mountain, TN (US); **Timothy S Clements**, Johnson City, TN (US); **Corbin Matthew Day**, Cleveland, TN (US); **Tyler James Sheffield**, Knoxville, TN (US)

(73) Assignee: **University of Tennessee Research Foundation**, Knoxville, TN (US)

(**) Term: **15 Years**

(21) Appl. No.: **29/786,908**

(22) Filed: **Jun. 3, 2021**

(51) **LOC (14) Cl.** **08-01**

(52) **U.S. Cl.**

USPC **D8/1; D4/122**

(57) **CLAIM**

The ornamental design for a chemical roller head core, as shown and described.

DESCRIPTION

FIG. 1 is a perspective view of a chemical roller head core; FIG. 2 is a front view thereof;

FIG. 3 is a rear view thereof;

FIG. 4 is a rightside view thereof;

FIG. 5 is a leftside view thereof;

FIG. 6 is a top view thereof;

FIG. 7 is a bottom view thereof; and,

FIG. 8 is a cross-sectional view thereof.

The broken lines in the drawings illustrate portions of the chemical roller head core that form no part of the claimed design.

1 Claim, 3 Drawing Sheets
